DOUBLE FLUID ENERGY MILL

Nicholas N. Stephanoff, Haverford, Pa., assignor to Fluid Energy Processing & Equipment Co., Hatfield, Pa., a corporation of Pennsylvania

Filed Jan. 22, 1968, Ser. No. 10,247

Term of patent 14 years

Int. Cl. D15—05

U.S. Cl. D55—1

FIG. 1

FIG. 2

FIG. 3

FIG. 1 is a front elevational view of a double fluid energy mill embodying my new design;

FIG. 2 is a side elevational view thereof; and

FIG. 3 is a top plan view thereof.

I claim:

The ornamental design for a double fluid energy mill, substantially as shown.
